UNITED STATES PATENT OFFICE.

HALLEY BUTZ, OF ALBION, INDIANA.

SWITCH-PLUG LOCK.

1,116,561.

Specification of Letters Patent. Patented Nov. 10, 1914.

Application filed April 3, 1913. Serial No. 758,681.

To all whom it may concern:

Be it known that I, HALLEY BUTZ, a citizen of the United States, residing at Albion, in the county of Noble and State of Indiana, 5 have invented certain new and useful Improvements in Switch-Plug Locks; and I do declare the following to be a full, clear, and exact description of the invention, such as will enable others skilled in the art to 10 which it appertains to make and use the same.

This invention relates to improvements in locking devices for switch plugs of motor vehicles.

15 One object of the invention is to provide a locking device of this character by means of which a switch plug may be locked when disengaged from its socket and partly retracted, thus obviating the necessity of entirely removing the plug, at the same time preventing an unauthorized person from inserting the plug and connecting up the switch.

Another object is to provide a combination locking device for switch plugs which may be changed when desired to form different combinations.

A further object is to provide a plug locking device for electric switches which will 30 be simple, strong, durable and inexpensive in construction, efficient and reliable in operation and which may be applied to the plugs of any motor vehicle or other form of electric switch.

35 With these and other objects in view, the invention consists of certain novel features of construction, and the combination and arrangement of parts as will be more fully described and claimed.

40 In the accompanying drawings: Figure 1 is a perspective view of a motor vehicle switch having my improved plug locking mechanism applied thereto; Fig. 2 is a central vertical longitudinal section thereof 45 showing the switch plug retracted or disengaged from its contact device and fastened in a retracted position by my improved locking mechanism; Fig. 3 is a similar view showing the plug projected or engaged with 50 the contact device of the switch; Fig. 4 is a vertical cross sectional view taken on the line 4—4 of Fig. 2; Fig. 5 is a detail per-

spective of the inner side of the outer locking disk of the device; Fig. 6 is an outer side view of the inner locking disk of the 55 device; Fig. 7 is a perspective view of a switch plug constructed in accordance with my invention.

In the embodiment of the invention I provide a casing 1 which may be of any 60 suitable shape or design and in the lower portion of which is arranged the usual contact terminals 2 and 3 of the circuits leading respectively to the magneto and to the 65 battery of the motor and which are provided with the usual binding screws to which the circuit wires are attached. Arranged in the lower portion of the casing 1 above the terminals 2 and 3 is the usual 70 plug socket 4 which is formed in two parts separated and insulated from each other by embedding the same in spaced recesses formed in the base or back plate of the casing or in any other suitable manner. To one member of the socket 4 is pivotally connected the usual switch lever 5 which extends downwardly and has its lower end 75 projecting through a slot in the lower end of the casing and provided with a knob or handle 6 whereby the switch is operated. 80 In the other member of the socket 4 is arranged a binding screw 7 to which the ground wire of the circuits is connected. The foregoing parts may be of the usual 85 or any approved construction and do not form a part of the present invention which applies to means for locking the plug 8 for connecting the members of the socket in a retracted position and thus positively preventing the completion of either of the 90 electric circuits and obviating the necessity of entirely removing the plug from the switch as is usually done to prevent tampering with the switch and starting of the motor by unauthorized persons.

95 The plug 8 comprises a metallic inner body portion 9 which is preferably cylindrical and has its outer end reduced to form a stop shoulder 10 and a shank 11. The shank 11 projects through and has a sliding engagement in an aperture 12 formed in the outer plate of the casing 1 in line with the center of the socket 4. On the outer end of the shank 11 is secured an op-

erating knob or handle 12 formed of suitable insulating or non-conducting material. The shank 11 of the plug is of sufficient length to permit the latter to be projected 5 into the socket 4 thereby forming an electrical connection between the two members or sections of the socket whereby when the switch lever 5 is swung into engagement with the terminals 2 and 3 of the magneto 10 and battery circuits, said circuits will be completed. Formed in the body 9 of the plug and spaced apart to a suitable distance are annular grooves 13 and 14 with which when the plug is in a retracted and inoperative 15 position are adapted to be engaged locking disks 15 and 16 hereinafter described.

The disks 15 and 16 are in the form of circular plates which are mounted on and insulated from an operating shaft 17 revolvably mounted in bearing apertures formed in the upper portion of the front and rear plates of the casing 1 as shown. 20 The disk 15 is keyed or otherwise fixedly mounted on the shaft 17 while the disk 16 is 25 loosely mounted thereon but is prevented from moving longitudinally by any suitable means commonly employed for this purpose in permutation locks. Sleeves 11' and 12' disposed on the shaft 17 as clearly shown in 30 Figs. 2 and 3 may be employed to prevent longitudinal movement of the loose disk. The outer end of the shaft 17 projects through the front plate of the casing and has fixed thereto a milled head 18 and an 35 indicating disk 19 having thereon an annular series of numerals or other indicating characters which are designed to co-act with an indicating mark 20 on the outer side of the front plate of the casing whereby 40 the position of the locking disks 15 and 16 may be determined.

At a suitable point in the edge of the disk 15 is formed a semi-circular notch 21 while at a suitable position in the periphery 45 of the disk 16 is formed a similar notch 22. In the disk 15 is also formed an annular series of threaded circular apertures 23 with one of which is adapted to be engaged a short stud 24 which projects from the inner 50 side of the disk 15. In the disk 16 is also formed a series of threaded apertures 25 with one of which is adapted to be engaged a short stud 26 which projects from the outer side of said disk and in the path of move- 55 ment of the stud 24 on the disk 15. The locking disks 15 and 16 are of such size and are mounted in such position in the upper portion of the casing 1 that the lower edges of the disk will engage the grooves 13 and 60 14 in the plug 8 when the latter is in a retracted position and out of engagement with the socket and will hold the plug in this position until the disks are turned to a position wherein the notches 21 and 22 therein 65 are in line with the plug at which time the

latter may be projected into the socket or retracted therefrom as will be readily understood. By thus constructing and arranging the locking disks 15 and 16 it will be seen that they may be turned by the knob 18 to bring the notches therein into and out of alinement with the plug 8 and in this operation the inner disk 16 is first adjusted by the outer disk 15. In thus adjusting the inner disk the outer disk 15 is turned 70 until the stud 24 thereof comes into engagement with the stud 26 on the disk 16 whereupon both disks are turned together until the notch 22 in the disk 16 is brought into alinement with the plug which position will 80 be indicated by the proper numeral or character on the indicating disk 19 of the knob 18 and the indicating mark 20 on the casing. After the inner disk 16 has thus been set the outer disk 15 is turned in a reverse 85 direction until the notch 21 in this disk has been brought into alinement with the plug, whereupon the latter will be released and may be projected into the socket 4. It will be understood that the positions of the 90 studs 24 and 26 and the notches 21 and 22 in the disks 15 and 16 are adjusted with respect to each other and the relative positions of these parts noted so that the numerals or characters on the disk 19 of the 95 knob will indicate to the person knowing the combination the position of the notches in the disks with respect to the plug. It will also be understood that by changing the positions of the studs 24 and 26 in the 100 threaded apertures of the disks that the combinations of the locking mechanism may be changed whenever desired.

From the foregoing description taken in connection with the accompanying drawings, the construction and operation of the invention will be readily understood without requiring a more extended explanation.

Various changes in the form, proportion, and the minor details of construction may 110 be resorted to without departing from the principle or sacrificing any of the advantages of the invention as claimed.

Having thus described my invention, what I claim is:

A switch of the character described comprising a casing, a plug socket disposed therein, a non-conducting shaft revolvably mounted and transversely disposed within said casing, disks carried by said shaft, one 120 of said disks being fixed to the shaft, the other loose, coacting means on the disks to cause the fixed one to move the other, a switch plug slidably mounted in said casing below the shaft therein and in alinement with the plug socket thereof, said switch plug having therein two adjacently disposed channels, which receive the edges of said disk, and retain the plug in its retracted position, said disks having notches 125

130

formed in their peripheries, which when brought into alinement below said shaft disengage said channels and permit the retraction of said plug, and an operating 5 knob on the shaft of said disk and having thereon characters which indicate the relative position of the notches in said disks with respect to said plug.

In testimony whereof I have hereunto set my hand in presence of two subscribing 10 witnesses.

HALLEY BUTZ.
